Stan Mattern
ATTORNEY

UNITED STATES PATENT OFFICE.

HARRY G. SPECHT, OF FAIRFIELD, CONNECTICUT.

CURTAIN ROLLER.

Application filed June 30, 1925. Serial No. 40,549.

This invention relates to curtain rollers and methods of producing the same, and particularly such rollers formed of sheet metal and to which a fabric curtain is adapted to be attached, an object of the invention being to provide a roller including means by which the curtain may be easily and reliably secured thereto.

It has been the usual practice, heretofore, with metal curtain rollers, to paste a fabric layer about the same, and to which the curtain was sewed by hand, this operation being time-consuming and the result being more or less unreliable due to the lack of uniformity in the work and the probability of the curtain becoming torn or loosened at its point of connection with the roller when fully drawn. Other attaching means, as clips, clamping wires, eyelets, etc., have also been employed, but these were expensive to produce and in certain respects unreliable, so that the method of pasting and hand sewing, above referred to, has been more generally used.

It is proposed in the present invention to provide a metal roller with a permanently attached flexible strip or flap extending longitudinally thereof, and to which the end of the fabric curtain may be sewed by machine stitch, so that a neat uniform, and reliable curtain and roller structure is produced. An object is to provide a combination roller and curtain attaching strip or flap attached to the roller along a longitudinal line thereof, one edge of the strip or flap being free for the attachment thereto of the curtain; and the invention further consists in the novel method of attaching such strip or flap during the formation of the roller.

A further object is to provide a metal roller formed from sheet metal rolled into tubular form, and including a longitudinal folded seam in which the strip or flap is secured, and further to provide a locked seam adapted to securely hold the strip or flap and to also prevent twisting and distortion of the roller.

With the above and other objects in view, an embodiment of the invention is shown in the accompanying drawings, and this embodiment will be hereinafter more fully de-

scribed with reference thereto, and the invention will be finally pointed out in the claims.

In the drawings:

Fig. 1 is a perspective view of a curtain roller, according to the present embodiment of the invention, a portion of the curtain being shown attached;

Figs. 2 to 7 are end edge views, showing the several steps in the formation of the roller from the flat sheet metal strip shown in Fig. 2 to the finished roller shown in Fig. 7;

Fig. 8 is an enlarged sectional view, showing the seam portion of the roller; and

Fig. 9 is a sectional view taken along the line 9—9 of Fig. 8.

Similar reference characters indicate corresponding parts throughout the several figures of the drawings.

Referring to the drawings, and more particularly to Figs. 1, 8 and 9 thereof, the curtain roller, according to the present embodiment of the invention, is in the form of a cylindrical tube 10 formed from strip sheet metal secured at its longitudinal edges by an interlocking seam, formed by flanges or folds 11 and 12 at the edges bent over in opposed relation and each engaged in the hook structure produced by the other. Within this seam there is engaged the folded over edge 13 of a longitudinal strip or flap 14 formed of suitable flexible material, as fabric, very thin metal, or the like. The seam is secured against opening by a series of knurling depressions 15 extending along its length, which prevent any possibility of the strip being pulled out, and further render the roller rigid against twisting and distortion, so that the parallel relation of the seam and strip 14 to the axis of the roller will be maintained.

The fabric curtain 16 is adapted to be secured to the strip 14, and this is preferably done by a machine stitch 17, the marginal edge of the curtain being preferably folded under, as shown.

The roller is adapted to be continuously formed upon a suitable rolling machine from a strip of sheet metal and a strip of suitable material for the strip or flap 14, suitable lengths being cut off to form the rollers. In

Figs. 2 to 7 I have illustrated the several steps in the formation of the roller. The flat strip of sheet metal enters the machine, as shown in Fig. 2, and first has the longitudinal flanges 11 and 12 bent upwardly and downwardly at its respective edges, the same then passing into relation with tube forming rollers, which gradually curl it, as shown in Figs. 4 and 5, bringing the flanges 11 and 12 into relation to 10 interlock with each other. At this point the strip 14 is introduced, its edge 13 being folded over by a suitable folding guide and fed into relation with the flange 12, whereupon the flanged end 11 is moved into engagement 15 therewith and the assembly compressed to 20 form the interlocking seam, as shown in Fig. 6, and in which the edge of the strip is secured. The tube now passes into relation with knurling rollers 18 and 19, which engage the seam at its inner and outer sides, compressing the same tightly together and producing the knurling depressions 15. As 30 the continuously formed tube emerges suitable curtain roller lengths are cut off.

25 It will be obvious that the rollers may be produced in any suitable diameters and lengths for use in households, automobiles, etc., and it is further pointed out that the invention is susceptible of use as a telescoping 35 adjustable roller by producing two lengths adapted to fit snugly and slidably one within the other, the surplus of the curtain attaching strip of the inner telescoping portion being torn off along the seam to a point contiguous 45 with the end of the outer telescoping portion, thus providing a continuous curtain attaching strip the length of the telescoping roller, and to which the curtain may be sewed. It is also pointed out that the flexible strip 14, secured in the seam of the roller, may, if desired, be of full curtain length to constitute 50 a curtain member adapted to be rolled upon the roller.

I have illustrated and described a preferred 45 and satisfactory embodiment of the invention, but it will be obvious that changes may be made therein, within the spirit and scope thereof, as defined in the appended claims.

Having thus described my invention, what 50 I claim and desire to secure by Letters Patent is:—

1. A curtain roller, including a sheet metal tubular roller member having a longitudinal locked seam arranged and constructed to rigidly secure the tubular relation of said member, and a relatively narrow flexible curtain attaching strip permanently secured in said seam along one longitudinal edge, the other longitudinal edge being free and adapted to have a curtain secured thereto by stitching.

2. A curtain roller, including a sheet metal tubular roller member having a longitudinal locked seam comprising longitudinal edge flanges of the sheet metal interlockingly connected to rigidly secure the tubular relation

of said member, and a flexible curtain member permanently secured in said seam and having a portion extended in folded relation within and about said interlocked flanges said seam being transversely knurled to prevent 70 longitudinal distortion of the seam and secure said curtain member against detachment.

3. A curtain roller, including a sheet metal tubular roller member having a longitudinal 75 locked seam comprising longitudinal edge flanges of the sheet metal respectively folded inwardly and outwardly and interlockingly engaged with each other and compressed so that said flanges are substantially in concentric lines with respect to the tube and adapted thereby to rigidly secure the tubular relation of said member, a flexible curtain member permanently secured in said seam along one longitudinal edge, said seam being transversely knurled to prevent longitudinal distortion of the seam and secure said curtain member against detachment.

Signed at Bridgeport, in the county of Fairfield, and State of Connecticut, this 24th 90 day of June, 1925.

HARRY G. SPECHT.
